UNITED STATES PATENT OFFICE.

HIRAM B. SMITH, OF ATLANTA, GEORGIA, ASSIGNOR OF ONE-HALF TO ED. HOLLAND, OF SAME PLACE.

HEAD AND BACK REST FOR RAILWAY-CARS.

SPECIFICATION forming part of Letters Patent No. 380,460, dated April 3, 1888.

Application filed September 7, 1887. Serial No. 249,059. (No model.)

To all whom it may concern:

Be it known that I, HIRAM B. SMITH, a citizen of the United States, residing at Atlanta, in the county of Fulton and State of Georgia, have invented a new and useful Head and Back Rest for Railway-Cars; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 The object of this invention is to supply a head and back rest for railway passenger-car seats, that will be capable of adjustment to different positions on the seat to allow the person using it to change position a corresponding number of times, and that will require very little room for packing, and be easily carried when not in use.

20 The device consists of two leaves hinged together in such a manner as to open out about 25 straight in one direction and fold together in the opposite direction, so as to occupy the least possible space, one leaf being provided with a yielding or elastic portion for the head to rest upon, and a supplemental leaf elastically arranged at the back, as will be herein-after fully described.

25 In the accompanying drawings, Figure 1 is a section of a railway passenger-car, showing my device placed in one of the positions for which it is adapted. Fig. 2 is a view of the back of my device, showing the leaves open and the general conformation of each. Fig. 3 is an edge view of same. Fig. 4 is an edge view of the same as seen when closed.

30 In the figures like reference-marks indicate corresponding parts in the several views.

35 A is the leaf having elastic material or portion inserted therein. B is the secondary leaf, C the elastically-attached leaf, and D are the 40 hinges. Placed over a hole or recess in the leaf A is the elastic or pliable material E, which may be of any material of sufficient elasticity or pliability to conform to a surface coming in contact therewith, for the purpose

of providing an easy place for the head of the 50 user. Between the leaf A and the leaf C are springs F, which are inserted for the purpose of counteracting the effect of the motion of the car, thus reducing the effect of the jar to a minimum.

55 G is the strip, of felt or other suitable material, for the purpose of further elasticity, and, more essentially, for preventing the wood-work of the car from being marred by contact with the device.

60 The construction of my device is as follows: The leaves are preferably made of one or more kinds of material built up; or, in the case of one or more kinds of wood, having each alternate layer of wood or veneer "crossed," or in 65 any other manner presenting a sufficiently strong texture to prevent splitting or warping, or the pulling off of the hinges by any extraordinary strain that might come upon them. The main leaf A is made in about the 70 form shown in the drawings, and has at or near its center a hole or recess for the purpose of applying the elastic material E. Around the edges, extending as far as desired, the strip G is placed, for the purposes hereinbefore mentioned. On the back of this leaf A is hinged, in any suitable manner, the leaf C, having a hole nearly corresponding to the hole in the leaf A. Between the leaves A and C are the springs F, which are preferably coiled 75 springs, although others would be equally applicable. The secondary leaf B is hinged to the leaf A by means of strong hinges, which are preferably riveted thereto. When opened to its full extent, the adjacent edges of the leaves 80 A and B come together on the opposite corners from the hinges, which hinges will then prevent the device from opening farther, and thus make a rigid support.

85 I do not confine myself to the specific shapes of the leaves, as these might be varied without a departure from the spirit of my invention.

90 Having thus described my invention, what I claim as new, and desire to secure by Letters 95 Patent of the United States, is—

In a head and back rest for railway-cars, a leaf, A, having an elastic portion, E, said leaf

being hinged to a leaf, B, in combination with a leaf, C, hinged to the leaf A, and having an opening to correspond with the elastic portion of leaf A, said leaves being provided with a protecting strip of felt, G, and the outer edges of said leaves A and C separated by a spring, F, substantially as shown and described.

In testimony whereof I affix my signature in presence of two witnesses.

HIRAM B. SMITH.
